UNITED STATES PATENT OFFICE

WILLIAM K. ECKHARD, OF DUNELLEN, NEW JERSEY, ASSIGNOR TO R. HOE & CO., INC.,
OF NEW YORK, N. Y., A CORPORATION OF NEW YORK

SHEET FEEDING MECHANISM

Application filed April 10, 1930. Serial No. 443,168.

The present invention relates to sheet feeding mechanism for machines that print on sheets of tinned iron, commercially known as tin, and on paste board and other relatively heavy materials that can be moved forward by means of a pushing device that engages the rear edge of the sheet.

The feeding mechanism disclosed herein differs from those heretofore used in that the reciprocating parts that operate the pushing device are relatively small and light in weight, they are driven by a chain that runs at a constant speed, and can be operated at higher speeds than the feeding devices of this class that were heretofore used, and still obtain accurate register when printing in a plurality of colors.

As shown and described herein, the mechanism is adapted particularly for use with a machine for printing on tin, but it will be understood that the device may also be applied to machines for operating on other materials and such use is considered to be within the scope of the claims.

An object of the invention is to provide a sheet feeding device for printing machines operating on tin and similar materials that can be operated at a high rate of speed.

Another object of the invention is to provide a sheet feeding mechanism for the service mentioned that will maintain accurate register of the printing.

It is also an object of the invention to provide a sheet feeding mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of

the invention herein disclosed may be made within the scope of what is claimed without departing from the spirit of the invention.

The preferred embodiment of the invention is illustrated in the accompanying drawings, wherein:

Figure 1 is a vertical sectional longitudinal view showing one end of the sheet feeding mechanism that is the subject of the present invention;

Figure 2 is a continuation of Figure 1 showing the other end of the feeding mechanism;

Figure 3 is a vertical endwise view showing a portion of the feeding mechanism as seen in the direction of the arrow 3 on Figure 2;

Figure 4 is a plan view of the feeding mechanism drawn to a smaller scale than Figures 1 and 2 and as viewed in the direction of arrow 4 of Figures 1 and 2;

Figure 5 shows a view of the pusher arm and associated parts; and

Figure 6 is a diagrammatic view showing a portion of the feeding mechanism, with the pusher mechanism, indicated in two of its positions.

Referring to the drawings, fragments of a form cylinder and an impression cylinder are shown, the form cylinder being indicated 11 and the impression cylinder 12. The feeding mechanism is supported on a frame of the usual type having side bars, one of which is shown and indicated at 13, these bars being connected at opposite ends with suitable members on the machine frame.

It will be understood that the mechanism shown in Figures 3 and 4 is preferably duplicated on the opposite side of the machine thus providing two pusher mechanisms that work in unison. As they are identical except that the relative position of the parts are reversed to make them right and left respectively, a description of one will suffice for both.

A cross brace of the machine is indicated

at 14. The side bars 13 rotatably support cross shafts 15, 16, 17 and 18 which have suitable bearings provided in the side frames. Shafts 15 and 18 are screw threaded on the portion shown in Figures 3 and 4, with a right hand thread and the portion of the shaft that is not shown, is threaded with a left hand thread. These shafts have sprockets 19 and 21 secured to them and are connected by a chain 22. A crank 23 is fitted to shaft 18 and may be employed to turn the shafts 15 and 18 simultaneously.

The pusher frame comprises the sub-frame members 24 and 25 that are connected by suitable cross members 26 and 26'. The sub-frame member 25 carries studs 27, 28, 29, 31 and 32 on which gears are rotatably supported. Any suitable means may be used to rotate the shaft 17 to which the gear 33 is attached. This drives a gear 34 on the shaft 16 and gear 35 also secured to shaft 16 meshes with gear 36 that rotates on the stud 29. The gear 36 meshes with idler gear 37 supported on the stud 32 and this in turn meshes with gear 38 that is secured to propeller roller 39 and rotates with it on the stud 31. The gear 36 meshes with the idler 41 which in turn meshes with gear 42 that is secured to and rotates with the propeller roller 43. A sprocket 44 is secured to the gear 36 and a sprocket 45 is rotatably supported on the stud 46 that is normally secured to the sub-frame member 25, but adjustable with relation thereto by an adjusting screw 47. A chain 48 connects the sprockets 44 and 45. The sub-frame members 24 and 25 are supported on a threaded shaft 18, the frame member 25 being provided with a screw threaded bushing 49 which engages the thread on the shaft 18. Similarly, the threaded bushing 51 engages the shaft 15 and it will be understood that by turning the crank 23, the pusher frame may be moved as a unit relative to the side frame 13 to accommodate wide or narrow sheets of the material that is being operated upon.

A track 52 is supported by being secured to the cross frame 26 at one end, and at the other end to a stud 50 secured to the frame 25, and the pusher carriage 53 slides forward and back thereon. The pusher carriage carries a shoe 54 that is secured to it by the screws 55, and a bracket 56 is secured to the shoe by the bolt 57 that passes through an elongated opening 58 in the bracket, thus permitting the bracket to be adjusted relative to the shoe over a limited distance, a greater range of adjustment being provided by removing the bolt 57 from the hole in which it is shown in Figure 4 and moving the bracket so that the bolt may be placed in another of the threaded holes 59 that are provided in the shoe. This arrangement for adjusting the pusher bracket relative to the pusher carriage provides a convenient means for adjusting the pusher to suit the size of the sheet

being operated upon and to accurately locate it in the correct position so that the sheet will be engaged by the grippers on the impression cylinder at the proper instant to insure accurate register of the printing.

The bracket 56 carries a stud 61 that pivotally supports the pusher arm guiding lever 62 which is provided with a stud 63 forming a pivotal connection for the pusher arm 64, to the extremity of which, the pusher plate 65 is secured. The pusher bracket is formed with a lug 66, and a rod 67 pivotally connected to the arm 64 passes through the lug and carries the spring 68 that is held on the rod by the washer 69 and the pin 71. The rod 67 is formed with an enlarged head at 72 that abuts against the lug 66. The spring thus acts to hold the pusher arm in the position shown in Figure 5.

The pusher bracket 56 carries a stud 73 that rotatably supports a roller 74 and the pusher carriage as shown herein is formed with a vertical channel or guide 75 in which a block 76 is fitted to slide. This block is secured to one of the pivot pins in the chain 48 and it will be understood that when the chain is driven by the sprocket 44 that the engagement of the block 76 with the pusher carriage will result in driving the pusher forward and back along the track 52.

A pusher guide which may have the form of a channel is indicated at 77 and is secured to a bracket 78 that is pivoted on a stud 79 secured to the track 52. A supporting rod 80 is pivotally connected to the guide 77 and slides in a hole in the cross member 26'. A spring 80' is placed on the rod and carries the weight of the guide 77. The guide 77 is pivotally connected to one end of the link 81, which has its opposite end pivoted on one extremity of the bell crank guide operating lever 82, that is pivoted on the stud 83 secured to the frame member 24. The opposite end of the lever 82 rotatably supports a roller 84 that is adapted to engage with the guide 110 operating cam 85 secured to the shaft 17. It will be understood that rotation of the shaft 17 will result in lowering one end of the guide 77 and alternately permitting it to be raised by the spring 80'. The roller 74 follows the channel in the guide 77 and raising and lowering the guide consequently results in imparting a corresponding motion to the pusher arm 64. The arrangement of the parts is such that as the pusher arm moves from right to left, referring to Figure 6, the pusher is carried in the position shown in full lines, and as the arm is moved backward from left to right, the pusher arm assumes the position shown in dotted lines.

Sheet guides 86 are secured to the frame member 14 and similar guides 87 extend backward therefrom forming a feed table, and preliminary side guides 88 are provided for giving an initial side register to the sheets.

In operation, a sheet is placed upon the feed table and pushed forward until it engages the propeller rollers 39. It will be understood that drop rollers not shown in the drawings, then come into action and the sheet is forwarded along the guides 87 and similarly engaged by the propeller rollers 43. The pusher arm will then rise behind the rear edge of the sheet as shown in full lines in Figure 6 and move forward, engaging the sheet and propelling it forward until it is taken by sheet grippers on the impression cylinder. The guides 77 will then be depressed and the pusher will return on a plane beneath the guides 87, allowing the succeeding sheet to pass over it when the operation will be repeated. The chain that is employed to drive the pusher mechanism supplies a continuous drive at the correct feeding speed and reverses the travel of the pusher while the driving block is turning about the sprockets, the reversal being accomplished without jar or objectionable vibration. It has been found in consequence, that a feeding device in which this mechanism is used will produce accurate register in printing when operating at much higher speeds than the mechanism heretofore used.

What I claim is:

- 20 1. In a sheet feeder, a reciprocating pusher, mechanism to raise and lower the pusher, a track on which the pusher travels, and means to move the pusher forward and backward on the track; said means including a chain supported on sprockets and operably connected to the pusher.
- 25 2. In a sheet feeder, a reciprocating pusher carriage, a track on which the carriage travels, an endless flexible operating member whereby the carriage is moved along the track, a pusher connected to the carriage, a guide adapted to govern the operation of the pusher, and means for raising and lowering the guide to raise and lower the pusher.
- 30 3. In a sheet feeder, a reciprocating pusher carriage, a track, means to move the carriage forward and backward on the track including an endless chain operably connected to the carriage, a pusher connected to the carriage, a guide adapted to govern the operation of the pusher, and means for raising the guide during motion of the pusher in one direction and for lowering it during motion in the opposite direction.
- 35 4. In a sheet feeder, a reciprocating pusher, a track on which the pusher travels, and means to move the pusher along the track; said means including a pusher carriage having a substantially vertically disposed channel on the carriage, a chain supported on sprockets and driven by suitable means, and a block secured to the chain and engaging the channel.
- 40 5. In a sheet feeder, a reciprocating pusher carriage movable on a track, a pusher

connected to the carriage, a guide adapted to govern the operation of the pusher and movable to a position substantially parallel to the track to raise the pusher and to another position to lower it, and an endless flexible driving member arranged to reciprocate the pusher. 70

6. In a sheet feeder, a reciprocating pusher carriage movable on a track, a pusher connected to the carriage, a guide arranged substantially parallel to the track and adapted to govern the operation of the pusher, means to move the guide out of parallelism with the track to change the path of the pusher, and an endless flexible driving member operably connected to the pusher. 75

7. In a sheet feeder, a track, a pusher carriage adapted to travel forward and backward on the track, a guide member associated with said carriage, a driving connection engaging said guide member and slidably substantially perpendicularly with respect to the track, and an endless flexible driving member to which the driving connection is pivotally secured. 85

8. In a sheet feeder, sheet guides, a reciprocating pusher carriage, a track beneath the level of the sheet guides on which the carriage slides, a pusher connected to the carriage and adapted to engage a sheet on the guides, and an endless flexible driving member connected to the pusher. 90

9. In a sheet feeder, sheet guides, a reciprocating pusher, a track beneath the level of the guides adapted to so guide the pusher that it engages the sheet, means to move the pusher forward and backward on the track, said means including a chain supported on sprockets and operably connected to the pusher. 100

10. In a sheet feeder, sheet guides, a reciprocating pusher mechanism, a device to raise and lower the pusher, a track beneath the level of the sheet guides on which the pusher travels, and means to move the pusher forward and backward on the track; said means including an endless flexible driving member operatively connected to the pusher. 110

11. In a sheet feeder, sheet guides, a pusher secured to a reciprocating pusher carriage, a track beneath the level of the sheet guides on which the pusher carriage travels, a substantially vertically disposed channel on the carriage, and means to move the carriage on the track including an endless flexible driving member carrying a block engaging the channel. 115

12. In a sheet feeder, sheet guides, a reciprocating pusher carriage, a track below the level of the sheet guides on which the carriage travels, a pusher connected to the carriage and adapted to engage the sheet, a guide adapted to govern the operation of the pusher, means for raising and lowering the guide to raise and lower the pusher, and 125

130

an endless flexible driving member operatively connected to the pusher carriage.

13. In a sheet feeder, sheet guides, a track below the level of the guides, a pusher mechanism adapted to travel forward and backward on the track, a guide member arranged substantially parallel to the track and adapted to govern the operation of the pusher mechanism, means to move the guide out of parallelism with the track to change the path of the pusher, and an endless flexible driving member operatively connected to the pusher.

14. In a sheet feeder, a track, a reciprocating pusher carriage adapted to travel on the track, a pusher bracket adjustable on the carriage, a pusher arm on the bracket and an endless flexible driving member whereby the carriage is moved along the track.

15. In a sheet feeder, a track, a reciprocating carriage on the track, a pusher adjustably connected to the carriage, a guide adapted to govern the operation of the pusher, means for raising and lowering the guide to raise and lower the pusher, and an endless flexible driving member whereby the pusher carriage is moved forward and backward on the track.

16. In a sheet feeder, sheet guides, a reciprocating carriage movable on a track, a pusher adjustably supported on the carriage and adapted to engage a sheet on the sheet guides, a movable pusher guide adapted to govern the operation of the pusher and movable to one position to raise the pusher and to another position to lower it, and an endless flexible driving member operatively connected to the pusher.

17. In a sheet feeder, sheet guides, a reciprocating carriage movable on a track, a pusher adjustably supported on the carriage and adapted to engage a sheet on the sheet guides, an endless flexible driving member operably connected to the pusher, a movable pusher guide adapted to govern the operation of the pusher and movable to one position to raise the pusher and to another position to lower it, and means to move the pusher guide in timed relation to the movement of the carriage.

18. In a sheet feeder, a reciprocating pusher device, a track for the pusher device, an endless flexible member adapted to move the pusher device forward and backward along the track, and means for moving the pusher device vertically in one direction to engage a sheet and in the opposite direction to avoid a sheet.

19. In a sheet feeder, a reciprocating pusher carriage, a track on which the carriage travels, a pusher connected to the carriage, means for moving the pusher vertically in one direction to engage a sheet and in the opposite direction to avoid a sheet, and an endless flexible operating member where-

by the carriage is moved forward and backward along the track.

20. In a sheet feeder, a reciprocating pusher, a track to guide the pusher, an endless flexible member having a driving connection and adapted to move the pusher along the track; said pusher being adjustable relative to the driving connection.

In testimony whereof, I affix my signature.

WILLIAM K. ECKHARD.
